SUCTION NOZZLE

Anders Eriksson-Jons, Stockholm, Sweden, assignor to Electrolux Corporation, Dover, Del., a corporation of Delaware

Application June 26, 1936, Serial No. 87,384
In Switzerland July 2, 1935

1 Claim. (Cl. 15—155)

My invention relates to suction nozzles for use in connection with a vacuum cleaner and particularly to duplex nozzles provided with openings of different sizes which may be selectively connected 5 to the source of suction. When the larger opening is in use it will cover a larger surface, thereby increasing the speed of cleaning. However, if a concentrated suction is desired in order to remove dirt which the larger opening will not pick 10 up, the smaller opening may be brought into use.

The objects and advantages of my invention will be apparent from the following description considered in connection with the accompanying drawing which forms part of this specification, 15 and of which:—

Fig. 1 is a cross-sectional view of a preferred embodiment of my invention;

Fig. 2 is a view similar to Fig. 1, but showing the parts in a different position;

Fig. 3 is a rear view of a portion of the nozzle showing a second embodiment of my invention; and

Fig. 4 is a view similar to Fig. 3, but showing the parts in a different position.

Referring more particularly to Figs. 1 and 2, reference character 10 designates a hollow conduit adapted to be connected to a source of suction and to act as a handle for moving the nozzle 11 over a surface to be cleaned.

The nozzle includes a preferably cylindrical portion 12 adapted to receive the end of conduit 10 and an elongated hollow body portion 13 formed with an elongated suction opening 14. Pivotally mounted at 15 within hollow portion 13 is a small nozzle member 16. Small nozzle 16 is rigidly connected to pivot 15 which is journaled in the hollow portion 13 and extends to the outside of the hollow portion where a handle 17 is rigidly secured thereto. A weight 18 is secured 40 to the end of the handle.

With the parts in the position shown in Fig. 1, the opening in smaller nozzle member 16 is aligned with cylindrical portion 12 whereby communication between these two parts is established. The presence of nozzle member 16 cuts off communication between elongated suction opening 14 and cylindrical portion 12. Application of a reduced pressure to conduit 10 hence causes air to flow in the small opening 19 in nozzle member 16, thus

producing a concentrated suction at this opening.

When it is desired to utilize the elongated opening 14, the handle 17 is turned in a clock-wise direction to the position shown in Fig. 2. In this position the smaller nozzle member 16 is removed from the open end of cylindrical portion 12, whereby the interior of the cylindrical portion is connected to the interior of the elongated portion 13. Hence, suction is applied to elongated suction opening 14.

In the embodiment above described the nozzle member 16 is retained in either of the positions shown in Figs. 1 or 2 by the action of weight 18 connected to the handle. Instead of employing a weight for this purpose, a spring 20 may have one end connected to a pin 21 secured to hollow portion 13 and the other end connected to an arm 22 rigid with pivot 15. In the position shown in Fig. 3, the spring 20 tends to rotate arm 22 in a counter clock-wise direction, thus maintaining smaller nozzle member 16 in an operative position. In the position of the parts shown in Fig. 4, on the other hand, spring 20 tends to rotate arm 22 in a clock-wise direction, thus maintaining the nozzle member 16 in an inoperative position.

While I have shown and described two more or less specific embodiments of my invention, it is to be understood that this has been done for purposes of illustration only, and that the scope of the invention is not to be limited thereby, but is to be determined by the appended claim viewed in the light of the prior art.

What I claim is:

A suction nozzle including a hollow body portion and a hollow tubular portion adapted to be connected to a source of suction, said nozzle being formed with a port between said portions, said body portion forming a large suction opening, a small tubular nozzle member pivotally mounted within said body portion, and means for pivoting said member to an operative position with one end in alignment with said port so that all air passes through said member and with the other end extending through said large opening, and to an inoperative position entirely within said body and out of alignment with said port.

ANDERS ERIKSSON-JONS.
